UNITED STATES PATENT OFFICE.

JACK I. POSES, OF NEW YORK, N. Y., ASSIGNOR TO A. A. VANTINE & CO. INC., OF NEW YORK, N. Y., A CORPORATION OF NEW YORK.

DESIGN FOR A BOTTLE OR SIMILAR CONTAINER.

Application filed March 25, 1927. Serial No. 21,347. Term of patent 3½ years.

To all whom it may concern:

Be it known that I, JACK I. POSES, a citizen of Russia, and a resident of the city of New York (borough of Manhattan), in the county and State of New York, have invented a new, original, and ornamental Design for a Bottle or Similar Container, of which the following is a specification, reference being had to the accompanying drawing, forming part thereof.

I claim:

The ornamental design for a bottle or similar container, substantially as shown.

JACK I. POSES.
